UNITED STATES PATENT OFFICE

BENJAMIN L. FRY, OF ST. LOUIS, MISSOURI

COIN-ACTUATED MECHANISM

Application filed August 19, 1929. Serial No. 386,871.

In an application, Serial No. 346,608, filed by me March 13, 1929, there is disclosed a coin-controlled vending machine for the delivery of package goods, such as cigarettes, which requires the deposit of two coins to permit and effect its operation and delivery of the goods. Where the selling price of the package is such that coins of unequal size and value, such as a dime and a nickel are required, the machine shown in said application has served satisfactorily and customers have shown no tendency to misunderstand the operation or deposit the coins in the wrong tubes. Where, however, the selling price of a package is such that two coins of equal value, such as two dimes, are required, it has frequently happened that the customer either through carelessness or forgetfulness deposits both coins in one coin chute, the result being that the machine is not only not rendered operative but is clogged, and it becomes necessary to disassemble the coin chute and the parts immediately associated therewith in order to put the machine in an operative condition. The object of the present invention is to provide a simple device whereby both coins may be inserted in one tube and will be automatically deflected into the proper relation to the operating mechanism. Another object of the present invention is to provide a construction of the coin chute which will facilitate the assembly of the same and avoid the use of fastening devices, such as rivets, screws or the like. An apparatus embodying the present invention is illustrated in the accompanying drawings and will be hereinafter first fully described and then more particularly defined in the appended claims.

In the drawings:

40 Figure 1 is a rear elevation of a vending machine having the present invention embodied therein,

45 Fig. 2 is an enlarged sectional elevation of the particular portion of the machine in which the invention is embodied,

50 Fig. 3 is an enlarged perspective view of a portion of the coin chute showing the parts disassembled but in their proper relative positions,

55 Fig. 4 is a vertical section of the parts

shown in Fig. 3 with the parts properly connected,

Fig. 5 is a similar view showing a different position of the coin deflector,

Fig. 6 is a section taken on the line 6—6 of Fig. 5, and

Fig. 7 is a detail cross section on the line 7—7 of Fig. 4.

In Fig. 1, there is shown at 1 the casing of a coin-controlled vending machine and in said machine there is shown, at one side, mechanism embodying two coin chutes 2 and 3 whereby the deposit of coins of different sizes and values is facilitated and by which the coins are directed to the operating mechanism, indicated generally at 4. At the right of Fig. 1 is shown mechanism adapted for operation by the deposit of two coins of the same value, each of said mechanisms including a single coin chute 5. The coin chute 5 comprises an upper tubular portion which is supported in any convenient manner within the casing of the machine and has its upper end disposed in juxtaposition to a coin slot in the front of the casing. The lower end of this upper section 6 is fitted in the upper end of a coupling and deflecting body 7 which is enlarged relative to the upper section and has its lower end engaged with two separate guiding tubes 8 leading to the operating mechanism, indicated at 9. The intermediate coupling body 7 is preferably formed of two similar castings each having its upper end contracted, as shown at 10, below which the casting is expanded, as shown at 11, and in the transverse web 12, at the lower end of the same, is formed a notch 13, the purpose of which will presently appear. The side webs of each casting are provided with lateral lugs 13 at their upper and lower extremities and intermediate the ends are smaller lugs 14, as shown, the edges of the side webs being recessed between the several lugs thereby forming slots 15 and 16 in the sides of the coupling, as clearly shown in Fig. 3. Upon

90 reference to said Fig. 3, it will be understood that the several lugs of the two castings mate when the castings are brought together and through the uppermost and lowermost of said lugs rivets or other fastenings, indicated at 100

17, are inserted to firmly secure the two castings together. About on a line with the lower edges of the lugs 14, a pivot pin 18 extends across the coupling body and this pivot pin carries a deflector 19 in the form of a lever having its upper arm very much longer than its lower arm whereby it will overbalance the lower arm and cause the reflector to normally assume an inclined position with its upper end projecting through one upper slot 15 and laterally beyond the coupling body. The lower shorter arm of the deflector has its side edges diverging downwardly so that they will direct a coin, indicated at 20, to the adjacent side of the coupling body and thereby cause it to assume a position over the upper end of one of the tubes 8. To avoid unnecessary weight, the lower end of the deflector is preferably forked, as shown at 21. The tubes 8, as shown in Fig. 3, are formed each of a single length of tubing folded to provide a rectangular shell having a longitudinal slot 22 in its outer wall, the tube or shell being bent adjacent its ends so that the ends will be offset relative to its intermediate portion and the tubes when in position will diverge downwardly so as to properly direct the coin to the controlling mechanism, as will be understood upon reference to Fig. 2. The lower ends of the sections 8 are fitted into the upper enlarged portions 23 of tubes which deliver the coin into the operating mechanism. In assembling the parts, the reduced upper end 10 is slipped over the lower end of the tube 6 and is so proportioned that it will closely encircle the tube and will be held thereto by frictional engagement. In similar manner, the upper ends of the respective tubes 8 are fitted about the lower end of the intermediate coupling body, the end walls of the tube lying closely against the ends of the webs 12, while the inner side wall of each tube 8 will pass up into the notches 13' and the slots 22 will receive the lowermost lugs 13, all of which is clearly shown in Figs. 3 to 7. The tubes 8 will bind snugly around the lower portion of the coupling body 12 and the lugs 13 will serve to guide the tubes in place so that they will not only be properly centered but they cannot be placed so that the intermediate portion will extend inwardly toward the central vertical line of the coupling body instead of outwardly with respect thereto as is desired. Normally the deflector 19 extends upwardly and laterally through one of the slots 15 so that its lower end will project somewhat through the slot 16 at the opposite side of the coupling body, as clearly shown in Figs. 4 and 5. When a coin is inserted through the coin slot in the front of the casing, it will gravitate through the section 6 of the coin chute and pass immediately into the coupling body. Its direct path is crossed by the deflector and, consequently, the coin will impinge upon the

deflector and will be thereby turned toward the adjacent side of the coupling body. While the deflector extends entirely across the path of the coin, its bulk is not sufficient to stop the progress of the coin especially when the momentum of the coin is accelerated by its drop through the upper section of the chute. Consequently, although the coin will be directed toward one side of the coupling body, its impact will serve to swing the deflector upon its pivot so that it will be shifted to the opposite side of the coupling body and the coin will be permitted to pass at once into one of the lower tubes 8. When the second coin is deposited, the action is repeated, except that the deflector is swung toward the opposite side of the coupling body and the coin entering said body is deflected into the other tube 8. This action is very clearly shown in Figs. 4 and 5 and will be understood readily from an inspection of said figures. The use of this device very effectually prevents both coins being delivered to the same portion of the actuating mechanism and, consequently, prevents the choking of the machine which has been heretofore of such frequent occurrence. The invention is very simple and may be applied to existing machines without great cost and it does not add materially to the weight of the machine nor increase the time required for the production or operation of the same.

Having thus described the invention, I claim:

1. A coin chute for vending machines comprising an upper section, an intermediate coupling section having its upper end fitted to the lower end of the upper section, and lower sections having their ends fitted to the lower end of the intermediate coupling section and diverging downwardly therefrom, the upper end of each lower section extending partly around the lower end of the intermediate section and having one wall extending into and across said section.

2. A coin chute for vending machines comprising a top section, a coupling section having its upper end fitted to the lower end of said top section and its body portion expanded relative to said upper end and constructed at its lower end to be engaged with a pair of bottom tubular members, a pair of bottom tubular members having their upper ends fitted to the lower end of the coupling member and diverging downwardly therefrom, the coupling member being provided with vertically extending slots in its opposite sides, and a deflector pivotally mounted within the coupling member and having its opposite ends extending respectively through slots in the opposite sides of said member.

3. A coin chute for vending machines comprising a single upper member, an intermediate coupling body fitted around the lower end of said upper member and having its

body portion expanded below its upper end, spaced tubular members having their upper ends engaged with and partly entering the lower end of the intermediate coupling member and extending downwardly therefrom, and a deflector pivotally mounted within the coupling body with its lower end portion adjacent the upper ends of the lower tubular members, said deflector normally extending across the coupling member and adapted upon impact of a coin to swing and direct the coin into one or the other of said lower tubular members.

4. A coin chute for vending machines comprising a single top section, an intermediate coupling member having its upper end fitted to the lower end of said top section and provided with vertically extending slots in its sides, bottom tubular members having their upper ends engaged with the lower end of the coupling member in spaced relation, and a deflector pivotally mounted within the coupling member and normally extending across the same so that its opposite ends will project through slots in the opposite sides of the member, the lower end walls of the upper slots constituting stops to limit the movement of the deflector.

5. A coin chute for vending machines comprising a top rectangular tube, a coupling body having its upper end reduced and shaped to snugly fit around the top tube, the lower end of the coupling body having vertically extending notches at the lower ends of its side walls and said coupling member consisting of mating sections having outwardly projecting lugs at the meeting edges of their side portions, lower tubular members having their upper ends formed to fit around the lower end of the coupling member and engage within the notches therein and provided in their outer sides with longitudinal slots engaging the lugs at the bottom of the coupling member.

45 In testimony whereof I affix my signature.
